UNITED STATES PATENT OFFICE.

EDWARD M. GRAHAM, OF CHICAGO, ILLINOIS.

DESIGN FOR A BICYCLE-FRAME.

SPECIFICATION forming part of Design No. 26,285, dated November 17, 1896.

Application filed October 5, 1896. Serial No. 607,966. Term of patent 7 years.

To all whom it may concern:

Be it known that I, EDWARD M. GRAHAM, a citizen of the United States, and a resident of the city of Chicago, in the county of Cook and State of Illinois, have invented and produced a new and original Design for Bicycle-Frames, of which the following is a specification, reference being had to the accompanying drawing, forming a part thereof.

10 The accompanying drawing is a perspective view of a bicycle-frame embodying my newly-invented design.

The leading features of my design consist in a curved bar A, the lower inner end of

which is connected by a cross-bar a to the 15 forks b of the seat-post B at a point between the upper and lower ends of the fork b, and also the lower curved bar C and the rear portion D, that are connected to the hub E, the bar C being also connected to the steering-post socket G.

I claim—

The design for a bicycle-frame herein shown and described.

EDWARD M. GRAHAM.
